ROLLING MILL

Frank J. Wood, New Rochelle, N. Y., assignor to
Erwin Loewy, New York, N. Y.

Application July 18, 1947, Serial No. 761,892

4 Claims. (Cl. 80—55)

1

This invention relates to rolling mills and particularly to an improved arrangement whereby a plurality of rolls and bearings may be inserted and removed as a unit from the mill, the rolls and bearings being assembled exteriorly of the mill so that the rolls and bearings may be inserted into the mill stand as an assembled unit and a minimum of time lost in the changing operation.

In rolling mill operation, the rolls frequently must be changed for various reasons, such as where various shapes are rolled which require substitution of rolls, or where repairs to the rolls must be made. In addition, various adjustments must be made to the rolls relative to each other, both axially and vertically.

Previously, the roll bearings and other elements associated therewith have been insertable and removable individually, requiring many operations in roll changing. A rolling mill stand normally has roll housings at each end comprising a pair of uprights defining a window serving as the support or receptacle for the roll bearings. In the type of roll housing in which the present invention especially is adapted for use, the roll housing uprights have a removable cap, the cap normally carrying suitable screw-down or vertical adjusting means. Previously, each time the rolls have been removed for any purpose, a substantially complete readjustment of the rolls and bearings relative to each other and the mill housings normally has been required.

One of the objects of the present invention is to simplify the manner and materially reduce the time in which a roll assembly can be removed, changed, and adjusted, whereby the loss in productive time of the mill due to the changing is reduced to a minimum.

Another object of the invention is to make possible the adjustment of the rolls and bearings as units before being inserted into the rolling mill housings.

One of the features of the invention is the provision of roll assembly carrier frames or yokes in which the rolls and roll bearings can be assembled and adjusted outside of the rolling mill, the assembled carrier frames being connected together and inserted as units through the top of the mill housings with the housing caps removed.

The invention is particularly adapted for use in a three-high rolling mill stand wherein the center roll is carried in a fixed vertical position in the mill housings and the outer rolls adjusted relative thereto.

In accordance with one aspect of the inven-

2

tion, roll assembly carrier frames are provided which can be connected together and lifted from the mill housings or inserted therein as units. Previous to insertion in the mill housings, the rolls and roll bearings can be assembled in each of the carrier frames and adjusted axially therein so that after the carrier frames are in the mill housings, the center carrier frame can be fastened in a fixed location in the housings and the adjoining carrier frames adjusted vertically relative to the mill housings and center roll, as desired.

The center roll assembly carrier frame can be in the form of a cradle or support having legs straddling the lower roll bearings and lower roll assembly carrier frame, the legs of said cradle being supported at fixed locations relative to the housings so as to position the center carrier frame in its desired vertical position.

10 The lower roll assembly carrier frame can be arranged so that it will be engaged by lugs on the cradle which extend under the lower carrier frame. In this manner, when the cradle is lifted, the lower carrier frame will be lifted therewith. Riders or roll guide bearings are provided for the center roll so as to clamp the roll and roll chocks or bearings in a predetermined vertical position, said riders having vertically adjustable devices to adjust the vertical pressure of said center roll on the roll bearings. Each of the carrier frames has a flange extending beyond the window housings so that the flanges can be clamped longitudinally relative to the housings, suitable adjusting means being provided for this purpose similar to that disclosed in applicant's copending application Serial No. 743,345 filed April 23, 1947.

15 In a two-piece roll bearing arrangement, the term "chock" is used herein to mean the bearing half against which pressure is exerted when material is being rolled. The term "roll guide bearing" is used herein in conjunction with two-part bearings to designate the bearings half opposite the roll chocks.

20 These and other objects, features, and advantages of the invention will become apparent from the following description and drawings which are merely exemplary.

Fig. 1 is an end elevation.

25 Fig. 2 is a front view of the rolling mill with the left portion thereof in section taken generally along the line 2—2 of Fig. 1, the screw-down mechanism at the top right portion being shown in section.

30 Fig. 3 is a sectional view of the cradle for sup-

porting the middle roll and engaging the lower roll carrier.

Fig. 4 is a schematic view of Fig. 1 with the cap shown removed and the roll insert partially lifted.

Fig. 5 is a sectional view through the upper roll carrier frame taken along the line 5-5 of Fig. 2.

In a preferred embodiment of the invention, rolls with two-piece bearings are shown, each bearing having chocks and a mating roll guide bearing or rider bearing, although it is to be understood that other types of bearings can be employed, such as roller bearings. Upper roll 10 has roll chocks 11a and 11b with anti-friction metal liners 12 engaging the roll necks 13 at each end of said roll. Upper roll guide bearings 14 are provided having anti-friction liners 15. Said roll guide bearings are urged upwardly by means of springs 16 supported in the center roll riders 17, there being a center roll rider provided at each end of the mill, said riders being positioned vertically in the bearings in a manner described hereafter.

Center roll 18 is carried in center roll chocks 19a and 19b having anti-friction liners 20, said anti-friction liners supporting the center roll necks 21. The chocks 19 are adjustably mounted in center roll assembly carrier cradle 22 in a manner which will be discussed at a later point. The lower roll 23 has lower roll necks 24 thereof supported in lower roll chocks 25a and 25b, said lower roll chocks 25a and 25b being mounted in the lower roll assembly carrier frame 26.

The mill stand has a pair of housings 60 and 61 (Figs. 1, 2), each of said housings having uprights 27 and 28, each of said uprights 27 and 28 defining a housing window 29 therebetween. The uprights are mounted on the mill stand base 30 in a well known manner. Cap 31 is removably held by cap bolts 32 to housing uprights 27 and 28. The cap can be provided with screw-downs 33, said screw-downs being operable separately by suitable driving mechanism to raise and lower the screw-down pads 34 (Fig. 1), said pads or screw-downs contacting the upper surface of upper roll assembly carrier frame 35. The lower roll assembly carrier frame 26 may be similarly supported by the lower adjustable screws 36 so as to vertically adjust the position of the lower carrier frame 26 in the housings.

Upper roll assembly carrier frame 35 has bolts 37 (Figs. 1, 4, 5) adjustably engaging the chocks 11b (Fig. 2). Screws 38 are provided for holding the left-hand chock 11a in the roll assembly carrier frame 35, said screws being adjustable if desired. In this manner, the thrust exerted by the roll bearings on the necks of the roll, and position of the roll relative to the carrier frame, can be adjusted. The thrust bearing portions 39 of the anti-friction liners 12 may be integral with or separate from the anti-friction liners.

The flange 40 of the roll assembly carrier frame 35 extends on either side of the housing window 29 and has slots 41 therein which will slip over the holding bolts 42, it being apparent that the vertical position of the carrier frame 35 can be made vertically adjustable relative to the housing. Said holding bolts 42 may be arranged as shown with a pair of adjustable nuts thereon between which the flange is held, so as to adjustably position the roll assembly carrier frame longitudinally or axially of the roll housings.

The center roll carrier frame 62 is made integral with the center roll cradle 22, although

other means of construction can be employed. The legs 43 of said cradle rest on the horizontal housing surface 44 so as to vertically position the cradle 22 relative to the housing.

5 Keeper plates 45 are provided with suitable bolts so as to clamp the flange of carrier frame 62 in position in the housings. Thus, it is seen that the center roll 18 is positioned vertically by the cradle 22, said cradle having a roll assembly carrier frame 62 integral therewith with roll chock 19a fastened thereto at the left end by bolts 46 and chock 19b adjustably positioned longitudinally of the carrier by adjustable bolts 47.

Riders 17 slip into the windows 29 of each of the roll housings and carry the anti-friction rider bearings 48. The vertical position of the riders can be adjusted by means of the wedge arrangement 49, said wedge arrangement having a movable wedge 50 mating with a surface 51 at the upper end of said riders. The wedges 50 are adjustable by means of wedge adjusting bolts 52 in a well known manner. By adjustment of the wedges, the vertical position of the riders 17 relative to the center roll 18 can be changed and thus govern the vertical pressure of the rider bearings 48 on the center roll necks 21 of the center roll 18. As mentioned previously, the riders 17 also serve as supports for the springs 16 which urge the upper roll guide bearings 14 upwardly and thus position the upper roll against the upper roll chocks 11 at all times. The legs 43 of the cradle may be supported on a wedge arrangement (not shown) similar to wedges 49 so as to adjust the vertical position of the center roll, if desired.

25 The lower roll 23 is carried in roll chocks 25a and 25b in the lower roll assembly carrier frame 26. The left lower roll chock 25a (Fig. 2) is held in place by bolts 53 and the right roll chock 25b is adjustably positioned longitudinally of the adjusting bolts 54 in a manner similar to the other carriers. The cradle legs 43 straddle the lower roll necks 28 and roll chocks 25a and 25b. The lower roll assembly carrier frame 26 has flanges 26a similar to the upper assembly carrier frame and can be clamped to the housing uprights in the same manner.

30 Connecting links 63 are provided to engage pins 64 and 65 located on the riders 17 and cradle 22, respectively, a set of pins and links being provided at each corner of the cradle 22. When it is desired to remove or insert the roll assemblies, links 63 are put into position on their pins and thus will connect together the riders and upper roll assembly with the center and lower rolls. It is apparent that various types of links and fastening means may be employed.

35 The legs 43 of the center roll cradle have extensions 66 projecting underneath the lower roll carrier frame 26. In the position of the lower frame shown in Fig. 2, the elevating screws have raised the lower roll assembly carrier frame 26 upwardly from the extensions 66. When the roll assembly is lifted upwardly, extensions 66 will contact the lower roll carrier frame 26 and lift it therewith.

40 When it is desired to remove the rolls from the roll housings, cap 31 is first removed after the nuts or bolts 32 have been disengaged. The links 63 are put into position on each corner of the center roll carrier and the riders. The keeper plates 45 are loosened or removed and the upper carrier holding bolts 42 and the lower carrier holding bolts 67 are loosened. A crane having hooks 69 then can grasp and lift upwardly the four lifting lugs 68 at the top of the riders 17.

As the assembly is lifted, it is seen that the upper roll assembly and carrier frame will be supported by the riders 17 through springs 16 and will be lifted therewith. Links 63 will cause the cradle 22 and center roll 18 to be lifted with the riders. Extensions 66 will contact the lower roll carrier frame 26 and lift the lower roll and carrier frame with the entire assembly. Fig. 4 shows the assembly partially lifted from the housings. After being lifted from the housings, the assembly can be taken to a point away from the rolling mill and the rolls replaced and adjusted as desired. The new rolls or bearings can be adjusted relative to each of the carrier frames and then the carrier frames reassembled.

When it is desired to replace the rolls, the assembly is connected together and reassembled in the roll housings in the reverse manner from that in which it was lifted. After the center roll is replaced, the keeper plates 45 are used to clamp the center frame in position. The cap 31 is then replaced and the upper and lower carrier frames then suitably adjusted by means of the screw-downs and elevating screws and then the holding bolts 65 and 67 tightened. The riders are then positioned by means of wedges 49 so as to cause the rider bearings to exert the desired pressure on the center roll bearing necks to properly position the center roll. It is evident that the upper and lower carrier frames can be adjusted longitudinally of the roll housings so that the upper and lower rolls will have the correct relative positions relative to the center roll.

Cradle 22 is shown in Fig. 3 with the center roll chocks 19a and 19b and the lower roll assembly carrier frame and roll chocks indicated in position in dot-dash lines to show the relative location of the parts. The struts 62a serve to connect together the two end portions of the cradle.

The invention described herein provides a means of assembling and disassembling the parts of a rolling mill so as to facilitate adjustment and replacement of the various parts. The details of construction shown can be varied without departing from the spirit of the invention as set forth in the appended claims.

What is claimed:

1. In a horizontal three-high rolling mill having a pair of housings with removable cap portions, an integral upper roll assembly carrier frame, an integral center roll assembly carrier frame and support therefor, a lower roll assembly carrier frame, roll bearing elements mounted at each end of each of said carrier frames, said carrier frames having bearing element supporting portions adjacent the ends thereof, means for longitudinally adjusting said bearing elements in said frames, rolls carried by said bearing elements in each of said carrier frames and positively positioned therein by said bearing elements, a center roll rider bearing means adjustably mounted in said housing and connectable therewith for holding said center roll in its supporting bearings, connections between said rider bearings and said upper roll carrier frame, said center roll support having legs straddling said lower roll carrier frame and having means adapted to connect said support with said lower carrier frame during insertion and removal of said assembly relative to said housings, and means to connect said center roll rider bearing means with said center roll carrier frame and support, so that said carrier frames and roll assemblies can be removed and inserted relative to

said housings through the top thereof as a unit when the cap portions are removed.

2. In a horizontal rolling mill having a pair of housings with removable cap portions, a plurality of separate roll assembly carrier frames insertable in said housings, said carrier frames extending along rolls to be carried thereby, said frames having bearing element carrying portions adjacent the ends thereof, roll bearing elements mounted at each end of each of said carrier frames in said bearing element carrying portions, adjusting means engaging at least one of said bearing elements and its carrier frame for longitudinally positioning said bearing elements relative to its carrier frame, rolls carried by said bearing elements in each of said carrier frames and adjustably positioned positively longitudinally therein by said bearing elements, and connections between said separate carrier frames joining said frames together for removal from and insertion in the mill housing as a unit through the top of said mill when the cap portions are removed, said rolls and bearing elements being adjustable and assemblable in their respective carrier frames exteriorly of the mill.

3. In a three-high horizontal rolling mill having a pair of housings with windows therein and removable cap portions, an integral upper roll assembly carrier frame, an integral center roll assembly carrier frame and support, an integral lower roll assembly carrier frame, roll bearing elements adjustably mounted at each end of each of said carrier frames, rolls carried by said bearing elements in each of said carrier frames and positioned longitudinally in said frame by said bearing elements, center roll rider bearing means mounted in the windows of each housing, means to position said center roll rider bearing means in said housings for holding said center roll in a fixed position relative thereto, spring supporting means between said rider center roll bearings and said upper roll bearing elements, connections between said center roll support and said lower roll carrier frame, said center roll support being connectible to said mill housings, connections between said center roll rider bearing means and said center roller assembly carrier frame, and means to connect a lifting apparatus with said rider bearing means whereby said roll assembly can be removed and inserted relative to said housings as a unit.

4. In a three-high rolling mill having a pair of housings, an integral upper roll assembly carrier frame, an integral center roll assembly carrier frame having legs depending from said center roll carrier frame adapted to straddle a lower roll assembly carrier frame, an integral lower roll assembly carrier frame, each of said carrier frames having roll bearing element carrying portions adjacent each end thereof, roll bearing elements mounted in each of said carrier roll bearing element carrying portions and rolls carried by said bearing elements, adjustable roll bearing element longitudinal positioning means positively adjustably positioning a roll relative to its carrier frame, center roll rider elements mounted in said housings for said center roll, means connecting said center roll in position in said housings, means adjustably positioning said upper and lower roll assembly carrier frames longitudinally relative to said housings, removable links connecting said center roll rider elements to said center roll assembly carrier frame, means connecting said center carrier frame with said lower roll carrier frame, and spring means in-

terconnecting said center roll rider elements and said upper roll assembly carrier frame, whereby said carrier frames, rolls, and bearings can be inserted and removed as a unit from said housings.
